Primary Examiner — George D. Kirschbaum*Assistant Examiner* — John P. Mccartney(74) *Attorney, Agent, or Firm* — Blanchard Horton PLLC(57) **CLAIM**

The ornamental design for an automobile grille, as shown and described.

DESCRIPTION

FIG. 1 is a perspective view of an automobile grille, showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing in the drawings is included for the purpose of illustrating and forms no part of the claimed design.

1 Claim, 5 Drawing Sheets(56)
